Attorney.

UNITED STATES PATENT OFFICE

HAROLD R. STOTT, OF PHILADELPHIA, PENNSYLVANIA

PHOTOGRAPHER'S FLASH GUN

Application filed June 1, 1928. Serial No. 282,240.

This invention relates to improvements in flash light devices for photographer's use in making flashlight photographs of objects not requiring instantaneous exposures when it is 5 desirable to produce a plurality of flashlights in different positions relatively to each object in making a single exposure thereof.

The object of the invention is to provide a flash gun of novel, simple and compact construction operated by a manually operable air discharging device which will, at each operation thereof, discharge and ignite a quantity of flashlight powder without refilling between the several discharges.

With the foregoing object and related objects in view, the invention consists of the elements and the combinations of them hereinafter described and claimed.

In the accompanying drawings, illustrating the invention,

Figure 1 is a longitudinal section through a flash gun showing one form of embodiment of my invention.

Figure 2 is a similar section, enlarged, on line 2—2 of Fig. 1, through the discharge end portion of the gun.

Figure 3 is an end view of the outer fitting of the powder container.

Figure 4 is an enlarged section through the valve device for controlling the passage of air from the air discharging means to the powder container.

Referring to the drawings, 3 designates an air tube having inner and outer fittings 4 and 5 screwed on to the respective ends thereof. Slidable in the outer fitting 5 is a centrally arranged rod 6 having a suitable handle 7 on the outer end thereof. The inner end of the rod 6 carries a piston 8 comprising a rigid collar 9 fixed to the rod and a flexible, cup-like collar 10. The collars 9 and 10 are fitted to the inner wall of the tube 3, and the rod 6 is fitted to the fitting 5 in a manner to permit air to enter the tube 3 through the fitting 5 and pass the piston 8 when the rod 6 is drawn outwardly, and to cause the flexible collar 10 to bind against the tube 3, and force air within the tube toward the inner fitting 4 when the rod 6 is pushed inwardly.

Screwed into the inner fitting 4 and pro-

jecting fixedly therefrom in axial alignment with the air tube 3 is the tubular body portion 11 of a powder container, and screwed on to the outer end of the tubular body 11 is a removable cover fitting 12 carrying a powder discharging nozzle 13 which is screwed on to fitting 12. The nozzle 13 is expanded and flattened at its outer end portion providing a broad and narrow powder discharging opening 14. The fitting 12 is provided with a partition wall 15 having a number of perforations 16 therein between the tubular body 11 and the nozzle 13 for the passage of powder from the powder container to the nozzle.

A yieldable valve device 17 is provided to permit air to pass from the inner end of the air tube 3 and into the powder container 11 when the rod 6 is pushed inwardly and to prevent the return of air from the powder container to the air tube 3 when the rod 6 is drawn outwardly. This valve device 17 comprises a separate fitting 18 screwed into the fitting 4 and having a passage 19 therein communicating at one end with the air tube 3, a valve stem 20 loosely fitted within the passage 19 and slideable therein, a valve head 21 on the stem 20 adapted to a seat 22 formed by the fitting 18 and surrounding the passage 19 and a spring 23 encircling the stem and bearing at its opposite ends against a shoulder on the fitting 18 and a head on the stem 20 and tending to force the valve head 21 toward the seat 22. When the rod 6 is drawn outwardly, the spring 23 seats the head 21 against the seat 22 and prevents the piston 8 from drawing air from the powder container 11; and, when the rod 6 is forced inwardly, the air within the air tube 3 is forced through the valve device 17 and into the powder container against the action of the valve spring 23.

Extending fixedly from the fitting 18 within the powder container 11 and communicating with the passage 19 within the fitting 18 is an air pipe 24 having two branches 25 and 26 which discharge into the powder container 11 at two spaced points 27 and 28 near the respective ends of the container, the discharging ends of the branch pipes being turned away from the nozzle 13 to direct the air

discharged therefrom toward the inner end of the powder container to agitate or stir the powder therein before the air discharged from the branch pipes discharges the powder within the container 11 out through the nozzle 13. The perforated partition 15 also assists in breaking up the powder and causing it to be discharged from the nozzle in a uniform stream.

Surrounding the flattened outer end portion of the nozzle 13 is a tray 29 which is fitted to the nozzle in a manner to be held in place thereon by friction and to be removable therefrom. This tray 29 contains a wick or pad 30 of absorbent material which surrounds the discharging opening 14 of the nozzle in close relation thereto and which is adapted to receive alcohol or other fuel to be burned as a means of igniting the powder discharged from the nozzle.

The tray 29 and nozzle 13 are provided with a removable cover 31 having a flange 32 which surrounds the tray 29 and which is held thereon by friction. The cover 31 is provided with a blade 33 projecting fixedly therefrom and constructed to enter the discharge opening 14 in the nozzle 13 and clear the same of powder when the cover 31 is applied to the nozzle and the tray, so that each time the cover is removed the nozzle will present a clear passage for the discharge of powder from the container 11.

Formed on the cover 31 is a small tank 34 for containing alcohol or other fuel to be poured therefrom upon the pad or wick 30 as needed. The tank 34 is provided with an inlet opening closed by a screw cap 35 for permitting the tank to be filled, and with a small outlet spout 36 through which the fuel may be poured upon the pad or wick 30. The spout 36 is provided with a suitable, removable screw cap or cover 37 to close the same.

The operation of the device, briefly described, is as follows:

The usual powdered magnesium metal is placed within the powder container 11, the cover 31 is removed from the nozzle 13 and tray 29, and a quantity of alcohol or other fuel is poured from the tank 34 upon the pad or wick 30 and ignited. The flash gun is now ready for use, and, each time the rod 6 is drawn outwardly and forced inwardly, the air from the tube 3 forced through the valve device 17 enters the powder container 11, agitates the powder therein and forces a portion thereof out through the nozzle 13, and the powder thus discharged from the nozzle is ignited by the flame of the burning fuel surrounding the nozzle and a flash of light is produced. This result takes place each time the rod 6 is drawn outwardly and forced inwardly until all the powder within the container has been used. The container may then be refilled with powder after the removal of the fitting 12, and, after the fit-

ting 12 has been replaced, the flash gun is again in readiness for the production of another series of flash lights.

I claim as my invention:

1. The combination of an air tube, a powder container communicating with one end of the air tube and comprising a tubular body having fittings screwed on to the respective ends thereof and a powder discharging nozzle screwed on to one of said fittings, the other of said fittings being screwed on to the air tube, a manually operable piston within the air tube for discharging air from the same to the container, a yieldable valve device permitting air to pass from the air tube to the container and preventing the return of the air to the air tube, and means to ignite powder discharged from the nozzle.

2. The combination of an air tube, a fitting screwed onto one end thereof, a tubular body screwed on to said fitting and forming a powder container, a fitting screwed on to the tubular body, a powder discharging nozzle screwed on to the last named fitting, the last named fitting having a plurality of openings therein affording communication between the tubular body and the nozzle, a manually operable piston within the air tube for discharging air from the same to the container, a yieldable valve device permitting air to pass from the air tube to the container and preventing the return of the air to the air tube, and means to ignite powder discharged from the nozzle.

3. The combination of a powder container having a nozzle provided with a powder discharging opening, a tray carried by and surrounding the nozzle and having absorbent material therein, means operable to discharge powder from the container and through the nozzle, and a removable cover having a flange surrounding and fitted to the tray and having a part adapted to enter the nozzle when the cover is applied to the tray.

4. The combination of a tubular container having a wall closing one end thereof and having a powder discharging nozzle connected to the other end thereof, a yieldable valve device permitting air to pass therethrough to the container and preventing the return of the air therethrough, a pipe extending from the discharge end of the valve device and having an open end directed toward the end wall of the container, and means operable to force air through said valve device.

In testimony whereof I affix my signature.

HAROLD R. STOTT.
